Primary Examiner — Susan Bennett Hattan*Assistant Examiner* — Janice Hallmark(74) *Attorney, Agent, or Firm* — Erickson Kernell Derousseau & Kleypas, LLC(57) **CLAIM**

The ornamental design for a lighter, as shown and described.

DESCRIPTION

FIG. 1 is a perspective view of the lighter in accordance with the present invention;

FIG. 2 is a top plan view of the lighter shown in FIG. 1;

FIG. 3 is a front elevation view of the lighter shown in FIG. 1; FIG. 4 is a side elevation view of the lighter shown in FIG. 1, the other side being a mirror image thereof; and,

FIG. 5 is a rear elevation view of the lighter shown in FIG. 1. The bottom of the lighter is not visible during normal use and, accordingly, is not shown and forms no part of the claimed design. The utilitarian features shown in broken line form no part of the claimed design.

1 Claim, 2 Drawing Sheets(56)
